UNITED STATES PATENT OFFICE.

WILLIAM D. LAUER, OF NEW YORK, N. Y.

CLOSET-SEAT COVER.

SPECIFICATION forming part of Letters Patent No. 746,111, dated December 8, 1903.

Application filed May 24, 1901. Serial No. 61,682. (No model.)

To all whom it may concern:

Be it known that I, WILLIAM D. LAUER, a citizen of the United States, residing in the borough of Manhattan, city, county, and State of New York, have invented certain new and useful Improvements in Closet-Seat Covers, of which the following is a specification.

My invention relates to a temporary cover for water-closet seats.

10 The cover is of such a nature that after use it may be done away with.

I will describe a cover embodying my invention and then point out the novel features in a claim.

15 In the accompanying drawings, Figure 1 is a top plan view of a seat-cover embodying my invention. Fig. 2 is a cross-sectional view of the cover in position on a closet-seat, the closet-seat also being in cross-section.

20 Similar letters of reference designate corresponding parts in both of the figures.

A represents a seat of a closet-bowl. It is provided with the usual opening, the wall of which may be straight or curved.

25 B represents a temporary cover for the seat A. It is preferably made of perishable material or materials, so that after its use it may be done away with. I preferably employ paper. The cover is here shown as being in

30 two pieces b b'. The piece b is adapted to conform to the contour of the seat A and the centrally-arranged piece b' to the wall of the opening in the seat A. The piece b' is provided with an opening, and it may be pro-
35 vided with cuts or slits in order that it may more easily adapt itself to the wall of the

opening. The piece b is of one thickness of paper and the piece b' of a different thickness. Preferably tissue-paper will be used for the piece b' and a thicker paper for the 40 piece b, though both pieces b b' may be of the same thickness. The tissue-paper is secured to the piece b by pasting or otherwise. If desired, the two pieces b b' may each be in several sections which are suitably joined together. 45

The covers may be arranged in pads and suspended in any desired manner, so that a cover may be torn off from the pad. Instead each cover may be provided with a tongue b², 50 50 in order that it may be suspended from a hook or nail. Several of such covers may be suspended from the same hook or nail.

What I claim as my invention is—

A cover for closet-seats comprising two 55 pieces of paper of relatively different thicknesses, one piece being of tissue-paper and secured to the under side of the thicker piece and both resting upon the seat and each having an opening of different size, the upper 60 thicker piece, formed with an opening conforming to that in the seat, the thinner piece having a smaller opening and being adapted to extend downward and to conform to the wall of the closet-seat opening. 65

In testimony whereof I have signed my name to this specification in the presence of two subscribing witnesses.

WILLIAM D. LAUER.
